(57) **CLAIM**

The ornamental design for an adjustable anchor for dental appliances, as shown and described.

DESCRIPTION

FIG. 1 is a front perspective view of a first embodiment of an adjustable anchor for dental appliances showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view showing a variant of the embodiment of FIGS. 1-8 including disclaimed alignment indicia;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a bottom view thereof;

FIG. 16 is a front perspective view of a second embodiment of an adjustable anchor for dental appliances which is a mirror image of the embodiment of FIGS. 1-8;

FIG. 17 is a rear perspective view thereof;

FIG. 18 is a front view thereof;

FIG. 19 is a rear view thereof;

FIG. 20 is a right side view thereof;

FIG. 21 is a left side view thereof;

FIG. 22 is a bottom view thereof;

FIG. 23 is a front perspective view showing a variant of the embodiment of FIGS. 16-22 including disclaimed alignment indicia;

FIG. 24 is a rear perspective view thereof;

FIG. 25 is a front view thereof;

FIG. 26 is a rear view thereof;

FIG. 27 is a right side view thereof;

FIG. 28 is a left side view thereof; and,

FIG. 29 is a bottom view thereof.

The broken lines shown in the figures are included for the purpose of illustrating portions of the adjustable anchor for dental appliances and form no part of the claimed design.
